UNITED STATES PATENT OFFICE.

JOHN T. FINLEY, OLEN I. FREEMAN, AND CHARLTON R. ROBERTS, OF ATLANTA,
GEORGIA.

TIE-PLATE.

Application filed October 5, 1923. Serial No. 666,840.

To all whom it may concern:

Be it known that we, JOHN T. FINLEY, OLEN I. FREEMAN, and CHARLTON R. ROBERTS, citizens of the United States, residing 5 at Atlanta, in the county of Fulton and State of Georgia, have invented certain new and useful Improvements in Tie-Plates, of which the following is a specification.

This invention relates to certain new and 10 useful improvements in tie plates by means of which railway rails are effectively secured to cross ties against upward or separating displacement.

The primary object of the invention is to 15 generally simplify and improve devices of the above kind, whereby the same may meet with all of the requirements for a successful commercial use, the device embracing the desired qualities of simplicity, durability, 20 and efficiency in operation.

Another object of the invention is to provide for the convenient and effective engagement of the plate with the base flanges of the railway rail.

25 Still another object of the invention is to provide efficient means for preventing creeping of the plate relative to the tie, whereby the rail is effectively held in proper position under all conditions.

30 Other objects will appear as the nature of the invention is better understood, and the same consists in the novel form, combination and arrangement of parts hereinafter more fully described, shown in the accompanying drawings, and claimed.

In the drawings, wherein like reference characters indicate corresponding parts throughout the several views:

Figure 1 is a top plan view of a tie plate 40 constructed in accordance with the present invention operatively engaged with a rail section.

Figure 2 is a view similar to Figure 1 showing the tie plate disposed prior to turning 45 movement of the same for engaging it with the rail as shown in Figure 1.

Figure 3 is an end elevational view of the device shown in Figure 1 with the spikes driven thru the plate into the tie.

50 Figure 4 is an enlarged perspective view of the tie plate looking at the top of the latter, and

Figure 5 is a view similar to Figure 4, looking at the bottom of the tie plate.

Referring more in detail to the drawings, 55 the present invention consists of an elongated metal plate 5, that is preferably cut in the desired size and shape from the previously rolled sheet, and stamped upwardly from the opposite sides of this plate are lips 6 respectively located near opposite ends of the plate 5 and normally struck upwardly a lesser distance than the thickness of the base flange 7 of the rail, so that when the plate is operatively engaged with the latter, 60 said lips will firmly grip the base flanges of the rail. The inner free corners of the lips 6 extend obliquely of the plate 5 as indicated at 8 by stamping the lips in this form from the plate during the manufacture of 70 the device, so that when the plate is disposed diagonally of the rail beneath the space of the latter as shown in Figure 2, with the diagonal edge 8 disposed against the vertical outer edge of one of the flanges 7 of 75 the rail, the adjacent lip 6 will ride onto the adjacent flange of the rail and permit the other lip 6 to engage the opposite flange of said rail. The plate is applied to the rail by clamping in this manner, it being necessary to drive the plate around to the position shown in Figure 1, by the use of a hammer or the like, so as to force the lips 6 onto the base flanges 7, due to the necessity of 80 flexing the lips 6 upwardly slightly, as they 85 are fully engaged with the base flanges 7. When the plate has been brought to the position shown in Figure 1, a firm engagement with the rail is therefore had.

The plate 5 is provided with a square 90 opening 9 opposite each of the lips 6, through which a spike 10 may be driven into the tie 11 for preventing turning movement of the tie plate from its operative position, and in order to prevent movement or creeping of the tie plate relative to the tie, the under surface of the plate 5 is formed with ribs 12. The ribs 12 are interrupted at intervals as at 13 between the lips 6 and also at the points where these 100 lips are formed, and said ribs extend longitudinally of the plate 5 or in a direction transversely of the rail, the interruption of the ribs providing shoulders at the spaced ends thereof as at 14, so that when the 105 ribs are embedded in the surface of the tie creeping is effectively prevented. Also, this insures smooth surfaces on the under

sides of the lips where they engage the upper surfaces of the flanges 7 of the rail.

The interruptions as at 13 in the ribs 12 between the lips 6 are similar to the interruptions at the points where the lips are struck from the plate so that the sheet from which the present devices are cut may be formed into tie plates of this kind without undue waste when it is found necessary to provide the lips in the original sheet at the point indicated at 13 between the lips 6 as shown. In other words, in some instances, the plates would be cut from the sheet so that the lips would be formed at the points indicated, but in other instances it may be found necessary to form the plates so that the ears would fall upon the sheet at the points where the interruptions are indicated at 13 on the present tie plate. This will be found to occur when a miscut or mistake in the manufacture of the plate is made, when cutting the same from the original sheet, and will enable the mistakes to be corrected without a great waste of material.

It will also be apparent that by providing the oblique inner corners 8 on the lips 6, the latter may be spaced comparatively close together and the plate may be of a minimum size while still permitting effective engagement of the lips upon the spaced flanges 7.

From the foregoing description, it is believed that the construction and operation, as well as the advantages of the present invention will be readily understood and appreciated by those skilled in the art.

Minor changes may be made without de-

parting from the spirit and scope of the invention as claimed.

What we claim as new is:

1. A tie plate comprising a flat metal plate having lips struck up therefrom respectively adjacent opposite ends of the plate and adjacent opposite longitudinal edges of the same in position to engage and ride over the upper surfaces of the opposed base flanges of a rail, and ribs formed upon the under surface of the plate extending longitudinally thereof, the ribs adjacent the longitudinal edges of said plate being interrupted at the points where the lips are struck up from the plate whereby the under faces of the lips will be substantially smooth.

2. A tie plate comprising a flat metal plate having a plurality of ribs extending longitudinally on the under surface of said plate, certain of the ribs being interrupted to provide spaced longitudinally aligning ribs, and lips struck up from the spaced portions between the ribs arranged adjacent the longitudinal edges of the plate whereby the undersurfaces of the lips will be substantially smooth and are adapted to engage and ride over the upper surfaces of the opposed base flanges of a rail, the lips being arranged at the opposite longitudinal edges and respectively adjacent the opposite ends of the plate.

In testimony whereof we affix our signatures.

JOHN T. FINLEY.
OLEN I. FREEMAN.
CHARLTON R. ROBERTS.
